(Cl. D7—7)

To all whom it may concern:

Be it known that I, Theodore Oscar Wegner, a subject of the Queen of Great Britain, residing at London, England, have invented a new, original, and ornamental Design for a Shoe, of which the following is a specification, reference being had to the accompanying drawing, forming part thereof.

The figure of the drawing is a front perspective view of the shoe in which the opposite side of the shoe has the same appearance as the illustrated side.

The drawing is lined for contrast.

I claim:

The ornamental design for a shoe, as shown and described.

THEODORE OSCAR WEGNER.
